FUSE SETTER

Harry F. Vickers, Washington, D. C., assignor, by
mesne assignments, to Vickers, Incorporated,
Detroit, Mich., a corporation of Michigan

Application September 27, 1935, Serial No. 42,365

10 Claims. (Cl. 89—1)

1 This invention relates to fuse setters, and has to do particularly with an ammunition unit of the type having a cartridge case including a main powder chamber and a projectile of the time fuse type mounted in the end of the cartridge case.

Heretofore in the handling of time fuse projectiles, it has been the practice to set the time fuses of the projectiles by hand so that such hand setting corresponds to a dial setting which indicates the desired setting to be obtained on the time fuse. This dial, which is usually positioned at a point which can be observed by the operator of the time fuses, has been heretofore maintained in the desired position by means of an indicating electrically controlled system, the source of the control of such system usually originating in a remote fire control station or range keeper. Usually the hand operated fuse setting mechanism is maintained adjacent the gun whereby to reduce the elapsed time between setting the fuse, loading and firing to a minimum. It will be obvious that four or five seconds may easily elapse between the setting of the fuse and the actual firing, and in case the target should be a diving aeroplane, for instance, such elapse in time would be a very serious one. It will also be seen that if the gun should be loaded and not fired immediately, the relationship between the fuse setting and the moving target becomes worse.

It is the object of the present invention to eliminate any error in the hand setting of the fuse to the signal or dial by interposing a power follow up system between the remote control station and the fuse setting means on the projectile whereby to continuously maintain the setting of the fuse to correspond with the dial or signal setting, without manual assistance.

In many instances the ammunition shell or unit is conveyed from a place of storage to a point adjacent the gun, and another object of the present invention is to provide means for continuously maintaining the setting of the fuse to correspond with the director signal while the shell is in the ammunition hoist; thus the fuse setting means on each projectile as it is being hoisted is correctly regulated whereby to save time in loading and eliminate the loss of time in moving the ammunition into the fuse setter. This continuous maintenance of the proper setting permits loading of the gun directly out of the hoist; and in most cases will eliminate the use of any fuse setting mechanism other than the hoist, reduce the hazards of handling, and

2 materially reduce the number of men exposed to the dangers which exist around an operating gun.

A further and very important object of the present invention is the provision of a novel cartridge and projectile in combination with fuse setting means and fuse setting control means whereby to continuously move or maintain the setting of the fuse of the projectile while the shell is in loaded position in the gun; by this method of continuous connection between the remote control station and the projectile, it will be seen that the fuse of the loaded projectile will be set automatically in accordance with the correct position as determined at the fire control station; the correct position of the fuse on the loaded projectile being thus maintained, at all times, up to the instant of fire. In this case the fuse is always set for the proper timing so that any movement of the target or any delay between loading and firing has no deleterious effect.

Other features of the invention have to do with details of arrangement and construction as will be more clearly set forth in the specification and claims.

In the drawings:

Fig. 1 is a view, largely diagrammatic, of one method of automatically maintaining the fuse setting of a shell preparatory to loading.

Fig. 2 is a diagrammatic elevation of a typical hoist unit such as used for hoisting shells from one elevation to a position adjacent the gun.

Fig. 3 is a diagrammatic view of a method of connecting the fire control station with a hoisting unit whereby to maintain the correct setting of the fuse during hoisting.

Fig. 4 is a sectional view taken on line 4—4 of Fig. 3.

Fig. 5 is a diagrammatic illustration of my preferred manner of controlling the fuse setting of the projectile, after loading, and up until the time of firing.

Fig. 6 is an enlarged sectional view of an ammunition shell illustrating particularly the manner of connecting and controlling the fuse setting means of the projectile with a point outside the cartridge case.

Figs. 7 and 8 are sectional views taken on lines 7—7 and 8—8, respectively, of Fig. 6.

The present invention resolves itself around two units which have been used as standard units or equipment for a good many years; the one unit, an ammunition shell of the type utilizing a time fuse, such shell being broadly

designated as 2, and the cartridge case thereof as at 3, the projectile as at 4 and fuse setting member as at 5; the other unit or equipment is what is known as a range keeper or fire control station, and is generally designated 6; such range keeper or fire control station being located at some point remote from the gun and manned by a skilled operator at that point; such fire control station being designed to transmit a director signal to a point adjacent the gun.

The present invention adapts itself to different types of equipment available on board a battleship or other unit utilizing a director signal and time fuse projectiles, and in Fig. 1 I have illustrated one embodiment wherein the shells 2 are shown in position in a standard type of fuse setting box generally indicated as at 7, such box usually having a shaft diagrammatically indicated as at 8 for moving the time setting members 5 to various positions corresponding to the director signal sent by the remote station 6. Instead of connecting wires 9 leading from the station 6 to some form of visual indicating means, I preferably connect the same into, and to control the operation of, an electrical Selsyn unit 10. This Selsyn unit is well known to those skilled in the art and is such an electrical unit as to accurately transmit movement emanating from the remote control station 6; in other words, any movement transmitted from the station 6 will be immediately and accurately transposed in a shaft 11 of such Selsyn 10. The movement of such shaft 11 may be transmitted through any motion transmitting means 12 to a shaft 13. The connection between the shaft 13 and the shaft 8 of the fuse setting box is by means of a follow up unit generally designated 14 and a motor 15, such follow up device being preferably of the balanced rotary type illustrated and described in my Patent Number 2,030,902 of February 18, 1936, and the motor 14 being any type of hydraulic motor such as a gear motor illustrated and described in said same patent. It will also be understood that such follow up motor unit also includes a pump 16 and supply tank 17.

In the modification illustrated in Figs. 2, 3 and 4, I have illustrated the adaptation of my control method to the standard type of ammunition hoist. As best shown in Fig. 2, a standard ammunition hoist is of the conveyor type wherein a plurality of the shells 2 are intermittently hoisted to a delivery position 18 which is preferably adjacent the breech of the gun. As best shown in Fig. 3, the wires 9 from the remote station 6 are connected to a combination of a Selsyn unit, hydraulic motor and follow up unit, which is diagrammatically indicated at 19, the translating movement being through the medium of a lever 20 connected to an oscillatable guide member 21 and pivoted at a point 22. A conveyor chain 23 of the hoist is provided with spaced steps 24 for receiving and positioning the shells 2. Spaced a predetermined distance from each step 24 are adjusting means 25 adapted to continuously control the position of the fuse setting means 5 of each shell loaded on the step 24 and being hoisted. The member 25 is connected by means of a lever 26 and linkage 27 with a control link 28 adapted to fit in the oscillatable guide member 21. The guide member 21 is preferably positioned adjacent the upper end of the hoist so that as the member 28, moving upwardly with the hoist, contacts with the guide 21, it will be seen that the position of the lever 21, and hence the fuse setting means 5, will be maintained or oscillated

back and forth in accordance with the setting of the remote control station 6. Inasmuch as the delivery position 18 of the hoist is preferably adjacent the breech of the gun, it will be seen that the time setting of the projectile will be maintained in its correct position, according to the director signal, up until the moment of loading of the gun.

Regardless of the method of loading of the gun or of the manner of keeping the fuse setting means in proper position, I have provided a further method of continuously setting the time fuse after the loading of the gun. The manner of continuously setting the fuse as illustrated in Fig. 1 or in Figs. 2 to 4 may be of assistance in helping the handling of the shells to load the same in proper position relative to the breech of the gun, but the ammunition unit and the control system illustrated in Figs. 5 to 8 will control the correct positioning of the fuse setter irrespective of loading.

In Fig. 6 I have illustrated the preferred form of ammunition shell which may be used in connection with the control system illustrated in Fig. 5. This shell 2 includes the usual cartridge case 3, the projectile 4 and a fuse setting means 5, as will be well understood by those skilled in the art. The improved control means consists of a shaft 29 connected to the fuse setter 5 and extending rearwardly through the projectile 4 into keyed relationship with a hollow shaft 30, which shaft 30 is provided with a plurality of small apertures 31 and which shaft extends through the rear end of the cartridge case 3. The rear portion of the shaft 30 is connected to a keyed member 32, which member 32 is hollow so as to receive a primer or firing cap 33, the ignition of the cap 33 causing the expanded gases to pass through the apertures 31 and ignite the powder in the main powder chamber 34.

The breech block of the gun is diagrammatically illustrated as at 35 and this breech block is provided with a gear member 36 having a portion adapted to slide around and fit into the key-way of the member 32 whereby rotation of the gear 36 will result in rotation of the shafts 30 and 29, and hence will cause movement of the fuse setting means 5. A firing pin 37, which is present in the usual breech block, passes through the hollow center of the gear 36 so as to contact with the cap 33 to fire the same.

As best shown in Fig. 5, the rotation of the fuse setting mechanism 5 through the gear 36 is by means of diagrammatically illustrated hydraulic circuit wherein 38 is the pump, 39 the motor and 40 the follow up valve, one part of which is operatively connected to the Selsyn unit 10. It will be seen that by this arrangement the shell may be loaded into the gun, the breech block moved to firing position and the fuse setting means 5 maintained in the proper position relative to the remote signal station 6 until the time of firing.

What I claim is:

1. A fuse setting system for time fuse projectiles, comprising a remote fire control station or range keeper, means forming a part of the breech block of the gun and connected with the projectile for adjusting the position of the time fuse after the projectile is loaded into the gun, a hydraulic pump, a motor for actuating said means, a follow-up valve connecting said pump and motor and means connecting said range keeper with said follow-up valve for continuously and positively setting the fuse in accordance with the conditions present at said range keeper.

2. A fuse setting system for time fuse projectiles comprising a remote fire control station or range keeper, hoist means for receiving and moving projectiles towards a delivery station, means adapted to engage a part of a projectile while positioned in said hoist for adjusting the time fuse setting thereof, power means for controlling said last named means whereby to set the time fuse while the projectile is positioned in said hoist and follow-up means operatively connected to said power means and through motion transmitting means to said range keeper for continuously maintaining the position of said time fuse corresponding to conditions at said range keeper, as long as the projectile remains in said hoist.

3. A fuse setting system for time fuse projectiles comprising a remote fire control station or range keeper, hoist means for receiving and moving single projectiles step by step towards a delivery station adapted to be positioned adjacent to but separate from the breech of the gun, means forming a part of the hoist for receiving the base of each projectile and means for contacting the time fuse to control rotation of the same about the axis of the projectile, a combined Selsyn, hydraulic motor and follow-up unit operatively connected between said range keeper and said fuse control means, the connection between the fuse control means and the combined Selsyn, hydraulic motor and follow-up unit being such as to continuously maintain or move the position of said time fuse corresponding to conditions at said range keeper while the projectile is in the hoist.

4. In a hoist for conveying time fuse projectiles towards a loading station, a conveyor chain, means on the chain for receiving a time fuse projectile and fuse setting means for said projectile connected to and movable with said chain.

5. In a hoist for conveying time fuse projectiles towards a loading station, a conveyor chain, means on the chain for receiving a time fuse projectile, fuse setting means for said projectile connected to and movable with said chain, and means operatively connected to said last named means for adjusting the fuse during hoisting movement.

6. In a hoist for conveying time fuse projectiles towards a loading station, a conveyor chain, means on the chain for receiving a time fuse projectile, fuse setting means for said projectile connected to and movable with said chain, and means operatively connected to said last named means for adjusting the fuse during hoisting movement and after attaining loading position.

7. In a hoist for conveying time fuse projectiles towards a loading station, a conveyor chain, means on the chain for receiving a time

fuse projectile, fuse setting means for said projectile connected to and movable with said chain, and means operatively connected to said last named means for effecting adjustment of the fuse in either direction about the axis of the projectile during hoisting movement.

8. A fuse setting system for time fuse projectiles comprising a remote fire control station or range keeper, means adapted to be positioned adjacent to but separate from the breech of the gun for receiving projectiles, means forming a part of said last named means for contacting the time fuse to control the rotation of the same in either direction about the axis of the projectile, power means connected with said last named means, a follow up unit connected to said power means for controlling the actuation of the same, and means operatively connected to said range keeper and said follow up unit for continuously moving said follow up unit in accordance with the actuation of the range keeper.

9. Projectile handling mechanism, comprising means for continuously generating and transmitting firing data for a gun, means for supporting a projectile, and means controlled by said generating and transmitting means for continuously maintaining a time fuse in a projectile in said supporting means set in accordance with said firing data throughout the time said projectile is in said supporting means.

10. Projectile handling mechanism, comprising means for continuously generating and transmitting firing data for a gun, means for supporting a projectile, and means carried by said supporting means and controlled by said generating and transmitting means for continuously maintaining a time fuse in a projectile in said supporting means set in accordance with said firing data throughout the time said projectile is in said supporting means.

HARRY F. VICKERS.
